INVENTOR
FRANCIS JOHN OSUCH.

ATTORNEY

UNITED STATES PATENT OFFICE

FRANCIS JOHN OSUCH, OF DETROIT, MICHIGAN

INDEX FOR BOUND VOLUMES

Application filed September 12, 1932. Serial No. 632,671.

The present invention pertains to a novel index adapted to be applied to a bound volume, such as a telephone directory, having alphabetically arranged or otherwise classified 5 contents.

The principal object of the invention is to provide a visible, external index so that any desired section of the volume may quickly be found without the necessity of turning the 10 pages. The utility of such a device in conjunction with a telephone directory will at once be apparent.

The invention further provides a sturdy and attractive cover for the bound volume 15 and one which may be used repeatedly for successive editions. In this connection, another object of the invention is to provide an inexpensive and simply constructed device having the uses already named.

20 The invention further embodies means for reinforcing the parts of the outer cover which carry the index leaves and, in a modified construction, enables quick insertion of additional book leaves or index cards without dismantling of the parts. The device herein disclosed is an improvement of the device 25 shown in my allowed application, Serial No. 568,442, filed October 12, 1931.

The invention is fully disclosed by way of 30 example in the following description and in the accompanying drawing, in which—

Figure 1 is a perspective view of the device;

Fig. 2 is a longitudinal section through the 35 back of the cover;

Fig. 3 is an elevation of the device, partly broken away, in open position;

Fig. 4 is a detail elevation of the cover; and

Fig. 5 is a detail section, partly in elevation, 40 of a modified form of bracket.

Reference to these views will now be made by use of like characters which are employed to designate corresponding parts throughout.

The cover in which the bound volume is 45 to be received comprises a central back piece 1 and sides or flaps 2 hingedly attached to the longitudinal edges thereof. The back strip 1 is somewhat wider and longer than the back or binding of the book to be received 50 between the covers.

To each of the ends of the back strip 1 is secured an angle bracket 3 extending transversely thereof. Each bracket has one side laid against the inner surface of the back strip and its other side lying substantially flush 55 with the corresponding extremity of the back piece 1 and extending inwardly of the cover device. The means for securing each bracket to the strip 1 comprises a rod 4 having bowed and threaded ends 5 passed through the vertical flange of the bracket and into the back piece 1 where they are screwed into nuts 6 inserted in the member 1 as shown more clearly in Figure 2. Lock nuts 7 may be threaded on the ends 5 and tightened against the vertical 60 flanges of the brackets 3 in order to make the adjustment more secure.

The device further includes a suitable series of index cards 8, each of which has a pair of apertured stubs 9 at the rear corners and 70 respectively receiving the upper and lower rods 4 as also shown in Figure 2. These members are obviously applied to the rods 4 by detaching the latter from the back strip 1. The forward edges of the leaves 8 carry the 75 usual index tabs 10 which are suitably staggered according to requirements as illustrated in Figure 1.

The device is designed to be used in conjunction with a bound volume having alphabetically arranged subject matter, such as 80 a telephone directory, but not having outwardly projecting index tabs to define the alphabetical separations. Such a volume may be mounted in the device in such a manner that the index cards 8 lie at the alphabetical separations. In order to mount the volume in this manner, the index cards 8 are detached from one or both of the rods 4, and if detached from only one of the rods, they 85 are swung on the other rod as far as possible away from the back strip 1. The bound edge of the bound volume is inserted between the rods 4 and laid against the back strip 1. The leaves 8 are then inserted in the proper places in the bound volume and are mounted on the rod or rods 4, as the case may be, after 90 which the ends of the latter are secured to the back strip 1 by the means already described. The leaves 11 of any given alpha- 95 100

betical section of the volume lie between adjacent index cards 8 as illustrated in Figure 1. If desired, the obverse face, or both faces, of each card 8 may be ruled as at 12 so that the more frequently used names of the corresponding initial letter and the associated telephone numbers may be written thereon, in order that these numbers may be found at a glance and without a search in the printed pages of the volume.

By reference to Figures 1 and 2, it will be seen that the horizontal flanges of the brackets 3 cover and thus protect the protruding tabs 9 of the index cards. Also, these brackets might be omitted, with a corresponding loss of function, but are preferred in that they reinforce the ends of the backing strip 1 which carry the rods 4 and the weight of the cards 8. Further, if desired, a handle or hanger 13 may be inserted between the member 1 and the upper bracket 3 with its ends apertured at 14 and penetrated by the bowed ends 5 of the rods 4 as shown in Figure 2.

25 In the modification shown in Figure 5, the bowed supporting rod for the index cards is made in two parts 15 and 16 which fit together at approximately the longitudinal center as indicated by the numeral 17. The section 15 may, for example, be hollow and the section 16 solid with a reduced end 18 which fits into the end of the section 15. The section 15 is secured to the back strip by a screw 19, and the section 16 by lock nuts 20 and 21. The nature of the joint 17, 18 is such that the sections may be separated thereat without releasing the securing devices at the other ends. The resiliency of the metal may, for example, furnish the necessary clearance for breaking the joint. Thus, additional leaves or index cards may be inserted at the center of the sectional rod without requiring detachment of the more permanent fastenings.

45 For use in connection with books that already have stiff covers, such as city directories, the covers 2 may be omitted, leaving only the backing strip 1 which carries the index leaves 8. The leaves would then be inserted in the book in the manner already described.

Further, the index leaves may carry advertising matter or a combination of ruled lines and advertising matter.

55 The mechanical means for securing the ends of the bowed rods to the backing strip is merely illustrative of various securing devices which will readily suggest themselves to a skilled mechanic.

60 It will now be evident that the invention provides a semi-permanent cover and index for a bound volume in the sense that the volume may be replaced readily whenever a new edition is issued, as in the case of telephone directories.

Although specific embodiments of the invention have been illustrated and described, it will be understood that various alterations in the details of construction may be made without departing from the scope of the invention, as indicated by the appended claims.

What I claim is:—

1. An index for a bound book comprising a backing member, rods secured thereto, fastening elements carried by said backing member and rigidly attaching said rod to said member and index cards having apertured ends adapted to receive said rods.
2. An index for a bound book comprising a backing member, rods secured to the ends thereof, fastening elements carried by said backing member and rigidly attaching said rod to said member and index cards having apertured ends adapted to receive said rods.
3. An index for a bound book comprising a backing member, reinforcing members secured to the ends thereof, rods secured to said reinforcing members, fastening elements carried by said backing member and rigidly attaching said rod to said member and index cards having apertured ends adapted to receive said rods.
4. An index for a bound book comprising a backing member, reinforcing members secured to the ends thereof, rods secured to said reinforcing members, fastening elements carried by said backing member and rigidly attaching said rod to said member and index cards having apertured ends adapted to receive said rods, said reinforcing members having horizontal flanges disposed outwardly of said rods.
5. An index for a bound book comprising a backing member, rods secured to the ends thereof, fastening elements carried by said backing member and rigidly attaching said rod to said member and index cards having apertured ends adapted to receive said rods, one of said rods being separable between its ends.
6. An index for a bound book comprising a backing member, rods secured to the ends thereof, fastening elements carried by said backing member and rigidly attaching said rod to said member and index cards having apertured ends adapted to receive said rods, said rods being separable between their ends.
7. An index for a bound book comprising a backing member, rods detachably secured thereto, fastening elements carried by said backing member and rigidly attaching said rod to said member and index cards having apertured ends adapted to receive said rods.
8. An index for a bound book comprising a backing member, rods detachably secured to the ends thereof, fastening elements carried by said backing member and rigidly attaching said rod to said member and index cards having apertured ends adapted to receive said rods.

9. An index for a bound book comprising a backing member, bowed rods secured thereto, fastening elements carried by said backing member and rigidly attaching said rod to said member and index cards having apertured ends adapted to receive said rods.

10. An index for a bound book comprising a backing member, bowed rods secured to the ends thereof, fastening elements carried by said backing member and rigidly attaching said rod to said member and index cards having apertured ends adapted to receive said rods.

11. An index for a bound book comprising a backing member, side cover members hingedly attached to the longitudinal edges of said backing member, rods secured thereto, fastening elements carried by said backing member and rigidly attaching said rod to said member and index cards having apertured ends adapted to receive said rods.

12. An index for a bound book comprising a backing member, side cover members hingedly attached to the longitudinal edges of said backing member, rods secured to the ends thereof, fastening elements carried by said backing member and rigidly attaching said rod to said member and index cards having apertured ends adapted to receive said rods.

13. An index for a bound book comprising a backing member, bowed rods positioned near the ends of said member and having their ends abutting one of the surfaces of said member, screws passed through said member from the other surface thereof and into the ends of said rods, and index cards having apertured ends receiving said rods.

14. An index for a bound book comprising a backing member, bowed rods positioned near the ends of said member and having their ends abutting one of the surfaces of said member, screws passed through said member from the other surface thereof and into the ends of said rods, said screws having their heads flush with the last named surface, and index cards having apertured ends receiving said rods.

50 In testimony whereof I affix my signature.
FRANCIS JOHN OSUCH.
